(57) CLAIM

The ornamental design for a finger-held golf ball scuff repair tool as shown and described.

DESCRIPTION

FIG. 1 is a perspective view of a finger-held golf ball scuff repair tool showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

1 Claim, 4 Drawing Sheets
